(57) **CLAIM**

The ornamental design for a hinge for glass shower door as shown and described.

DESCRIPTION

FIG. 1 is a front elevation view of a hinge for glass shower door, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front perspective view thereof; and,

FIG. 8 is a rear perspective view thereof.

The broken lines in the drawings illustrate portions of the hinge for glass shower door that form no part of the claimed design.

1 Claim, 8 Drawing Sheets
